CLAIM

The ornamental design for a liquid fillable bomb blast inhibitor, as shown and described.

DESCRIPTION

FIG. 1 is an exploded perspective view of a liquid fillable bomb blast inhibitor showing my new design; FIG. 2 is a side elevational view thereof with the lid raised and with the opposite side being a mirror image thereof;

FIG. 3 is a top plan view thereof;

FIG. 4 is a bottom plan view; and,

FIG. 5 is a perspective view thereof fully assembled.

FIG. 1

FIG. 2

FIG. 3

FIG. 4

FIG. 5
